SOUND PRODUCING DEVICE FOR FOOT-WEAR

Salvatore Capezio, East Paterson, N. J.

Application May 8, 1935, Serial No. 20,311

15 Claims. (Cl. 36—8.3)

This invention relates to a sound producing device for footwear, and more particularly to a tap for dancers, optionally combinable with a jingle.

5 The primary object of my invention resides in the provision of a tap improved by the addition of an optionally usable jingle. Further objects are to make this addition in so inexpensive a manner that the tap may be sold without extra charge, 10 the jingle being used or discarded at the whim of the purchaser; to so carry the jingle within the tap that the exterior of the tap is not modified and instead retains its continuous bottom surface, with consequent freedom from the possibility 15 of tripping or catching the jingle mechanism on the floor; and, from a different aspect, to provide jingle mechanism the moving part of which is completely enclosed or protectively housed.

Still another object of my invention is to 20 improve the sound producing characteristics of the device both with respect to tap sounds and jingle sounds; and to this end the tap is hollowed to form a sound amplifying chamber which is left open at one end to form a sound discharge passage, and it is this chamber which is used to 25 loosely carry and to protectively house the jingle.

The chamber is bounded by a flange having a relatively broad top surface for supporting the weight of the dancer, and in accordance with 30 still another feature and object of my invention, the surface of this flange is sloped downwardly and inwardly from the outer edge of the tap in order to insure close contact between the tap and the shoe at the periphery of the tap.

35 To the accomplishment of the foregoing and other objects which will hereinafter appear, my invention consists in the tap and jingle elements and their relation one to the other, as herein-after are more particularly described in the specification and sought to be defined in the claims. The specification is accompanied by a drawing in which:

Fig. 1 is a partially sectioned side elevation of a heel tap embodying features of my invention 45 applied to a dancing shoe;

Fig. 2 is an inverted plan view of the same;

Fig. 3 is a plan view of the tap before application to the shoe and is taken looking in the direction of the arrows 3—3 in Fig. 1;

50 Fig. 4 is a longitudinal section taken in elevation through the tap in the plane of the line 4—4 of Fig. 3;

Fig. 5 is a transverse section taken in elevation through the tap, looking in the plane of the 55 line 5—5 of Fig. 3;

Fig. 6 is a partially sectioned elevation of a modification designed for use on high heels;

Fig. 7 is a horizontal section taken in the plane of the line 7—7 of Fig. 6;

Fig. 8 is a section similar to Fig. 6 but showing 5 a modification;

Fig. 9 is a partially sectioned side elevation of a toe tap embodying features of my invention; and

Fig. 10 is a plan view of the same before being 10 applied to the sole of the shoe.

Referring to the drawing and more particularly to Figs. 1 through 5, I show a heel tap 12 secured to the heel 14 of a shoe 16. The tap 12 may be cast of an aluminum alloy or other satisfactory light-weight metal and is hollowed on its upper surface to form a sound amplifying chamber 18 bounded by a flange or side wall 20 which terminates at the forward end of the tap or at the points 22 (Fig. 3), thereby opening the 20 forward end of the chamber 18 to form a sound discharge passage. This end may be indented at 23 when viewed in plan. Flange 20 is pierced with a series of holes 24 for fastening means here exemplified by a special form of nail 26 used 25 to secure the tap to the heel 14.

In accordance with my invention, the tap may be combined with a jingle here exemplified by a washer 30 dimensioned to fit within the chamber 18 and to be freely movable therein preferably 30 both vertically and laterally. In order to hold the washer or jingle 30 within the tap, I provide an upstanding pin 32 preferably cast integrally with the tap. The jingle 30 is slipped over pin 32 before nailing the tap to the bottom of the shoe. 35 Inasmuch as pin 32 projects upwardly to the bottom surface of the heel, the jingle is anchored in place against loss through the open forward end of the tap. The hole in washer 30 is, of course, very much larger than pin 32, thus providing ample room for adequate movement of the washer to produce the desired jingling sound. 40

It will be noted that the tap is in every way a practical and serviceable tap entirely apart from the jingling feature. In fact, the pin 32 acts as 45 an additional support to strengthen the bottom wall of the tap against any stress which might be caused by the weight of the dancer. The jingling element 30 is exceedingly inexpensive and may be and preferably is sold along with the tap without 50 increasing the cost or necessary sales price of the tap. The purchaser then has the option of using the tap with or without the jingling feature, and if a plain tap is desired, the washer is discarded and the tap nailed in place alone. On the other 55

hand, when the jingle is used, the tap is itself helpful because it acts as a complete protective housing for the jingle.

The flange 20 around the periphery of the tap is preferably broad but may, if desired, be channeled, thus leaving two narrower flanges 34 and 36. The top surface of flange 20 even if unchanneled is preferably sloped downwardly and inwardly, and this manifests itself, when the flange 10 is channeled, by the fact that the inner wall 36 is lower than the outer wall 34. This slope at the top of flange 20 is desirable in order to insure perfect contact between the tap and the bottom of the heel around the outer periphery of the tap, 15 or, in other words, to guard against a gap or visible space showing at the outer periphery of the tap should some irregularity on the heel bottom engage a part of the flange at the inner wall 36. The slope is preferably made moderate or 20 slight in order that the supporting action of the inner as well as the outer wall may come into play in the event of heavy loading of the tap.

The bottom surface of the tap is preferably provided with a raised peripheral portion 38 near 25 the rear of the tap, which tapers off somewhat toward the forward ends 40. This construction is desirable in order to provide a part on the tap which takes the blow of heel taps and the consequent wear caused thereby without marring and 30 wearing the main polished bottom surface of the tap until after the tap has seen long use. A second step may be formed on the bottom of the tap at 42 which strengthens the tap, begins to take wear after the part 38 has been subjected to substantial wear, and which may be used to receive 35 the name of the manufacturer.

The heel tap may be modified for use on high heels, and such a modification is shown in Figs. 6 and 7 of the drawing. In this case the body of 40 the tap 50 is given an external configuration comparable to that of the bottom or leather or rubber lift of a high heel 52. The heel is usually made of wood and the bottom lift is preferably removed before applying the tap 50 in order not to vary 45 the over-all height of the heel. The tap 50 is hollowed on its upper surface to form a sound chamber 53 bounded by a flange 54 and preferably open at the forward end 56. The top surface of flange 54 slopes downwardly and inwardly in 50 order to insure tight contact against the bottom of the heel at the outer periphery of the tap. Flange 54 is substantial in width, particularly so at the forward ends 58 which are perforated with 55 holes 60 for fastening means, preferably long slender wood screws 62. A third hole is provided through the bottom of the tap for a third screw 64 which acts as a locating pin for a suitable washer-like jingle 66. The use of the wood screw 64 as a locating pin is desirable because the 60 screw then serves a dual function in that it provides a secure mounting of the tap on the heel.

It will be understood that the jingle 66 is so dimensioned as to be freely movable within the tap, thus producing the desired sound. It will 65 also be understood that the open forward end of the chamber 53 serves as a sound passage for either tap or jingle sounds. Furthermore, the jingle element 66 is simply an inexpensive washer made of brass or other suitable metal, and may 70 be delivered with the tap without extra charge, thus giving the purchaser the option of using or discarding the jingle, as desired.

In Fig. 8 I show a slight modification of the tap last described, in which a jingle 70 is located by 75 a pin 72 driven into the heel 74 without passing

through the body of the tap. The third screw for securing the tap to the heel is indicated at 76 and may be located near the rear edge of the tap. Reverting to Fig. 7, I may further point out that by giving the jingle 66 a diameter greater than the space between the broadened ends 58 of the tap flange 54, the jingle may be retained against loss without using a locating pin. 5

Most of the features of my invention heretofore described are applicable to toe taps as well as to 10 heel taps, and this is illustrated in Figs. 9 and 10 in which I show a cast toe tap 80 hollowed on its upper surface to form a sound amplifying chamber 82 bounded by a broad peripheral flange 84. Flange 84 terminates at the points 86 at the rear 15 end of the tap, thus leaving the rear end of sound chamber 82 open to form a passage for better 20 egress of sound. A locating pin 88 is cast integrally with the tap and serves to effectively hold in place a loose or movable jingle washer 90. As before, the jingle is negligible in cost and its use optional with the purchaser. 20

The top surface of the flange 84 is sloped downwardly and inwardly, as is most clearly shown at 92 in Fig. 9, thereby guarding against the formation of a visible breach or space between the tap and the shoe at the outer periphery of the tap. The flange is pierced with suitable nail holes 84 through which fastening means such as the fluted 30 nails 96 are driven.

It is believed that the mode of constructing and using as well as the many advantages of my improved combination of tap and jingle will be apparent from the foregoing detailed description thereof. It will also be apparent that while I 35 have shown and described my invention in preferred forms, many changes and modifications may be made in the structures disclosed without departing from the spirit of the invention defined in the following claims. 40

I claim:

1. A jingle tap comprising a metallic tap hollowed on its upper surface to form a chamber, a washer within said chamber so dimensioned as to be movable therein, and a pin passing through said washer. 45

2. A jingle tap comprising a metallic tap hollowed on its upper surface to form a chamber open at one end, a washer within said chamber so dimensioned as to be movable both vertically and 50 sidewardly therein, and a stop pin passing through said washer.

3. A tap assembly comprising a metallic tap member of generally conventional form, said tap being thin relative to its area and being adapted to be secured outside of and beneath an ordinary shoe bottom, and said tap being hollowed on its upper surface to form a sound chamber, and having a locating pin within said chamber, said pin being adapted to retain an optionally usable 55 jingle washer loosely in place.

4. A tap comprising a metallic tap member hollowed on its upper surface to form a chamber bounded by a peripheral flange adapted to be secured against the bottom of a shoe, said chamber being open at one end, and a locating pin for 60 said chamber adapted to retain an optionally usable jingle washer in place.

5. A tap comprising a metallic tap body adapted to be secured to the bottom of a shoe, said 70 body being hollowed on its upper surface to form a chamber bounded by a supporting flange, the top surface of the flange sloping downwardly and inwardly in order to insure close contact between the shoe and the periphery of the tap, and 75

a pin in said chamber having a height such as to support the bottom wall of the tap when the tap is applied to a shoe.

6. A tap comprising a metallic tap body adapted to be secured to the bottom of a shoe, said body being hollowed on its upper surface to form a chamber bounded by a supporting flange, said flange being discontinued at one end of the tap, the top surface of the flange sloping downwardly and inwardly to insure close contact between the shoe and the periphery of the tap, holes for fastening means passing through said flange, and a locating pin for said chamber for retaining an optionally usable jingle washer in place.
- 15 7. A heel tap comprising a metal tap body hollowed on its upper surface to form a sound amplifying chamber bounded by a supporting flange, said flange being terminated at the forward end of the tap to open the chamber, said flange being channeled and the inner side of the channel being lower than the outer side of the channel in order to insure a close fit between the outer side of the channel and a heel to which the tap is applied.
- 25 8. A heel tap comprising a metal tap body hollowed on its upper surface to form a chamber bounded by a supporting flange, said flange being terminated at the forward end of the tap, said flange being channeled and the inner side 30 of the channel being lower than the outer side of the channel, an optionally usable jingle washer dimensioned to be movable in said chamber, and an upright locating pin in said chamber for the jingle washer.
- 35 9. A heel tap comprising a metal tap body hollowed on its upper surface to form a chamber bounded by a supporting flange, said flange being terminated at the forward end of the tap, said flange being channeled and the inner side 40 of the channel being lower than the outer side of the channel, an optionally usable jingle washer dimensioned to be movable in said chamber, and an upright locating pin cast integrally with the tap in said chamber for the jingle washer, the bottom of said tap being so shaped as to present a protruding bottom surface at its rear periphery.
- 45 10. A heel tap for use on high heels, said tap comprising a metallic tap body hollowed on its upper surface to form a chamber, a plurality of holes for fastening means passing through said tap, one of said holes being located at approximately the center of the chamber and receiving an attaching screw adapted to act as a retaining pin for a jingle washer, and an optionally usable 50 jingle washer so dimensioned as to be movable in the chamber.
- 55 11. A heel tap for use on high heels, said tap comprising a metallic tap body hollowed on its upper surface to form a chamber open at its

forward end and bounded by a supporting flange the top surface of which slopes inwardly and downwardly, a plurality of holes for fastening means passing through said tap, one of said holes being located at approximately the middle of the 5 chamber and receiving an attaching screw adapted to act as a retaining pin for a jingle washer.

12. A heel tap for use on high heels, said tap comprising a metallic tap body the exterior of which is shaped like the bottom lift of a high heel, said tap being hollowed on its upper surface to form a chamber open at its forward edge and bounded by a supporting flange the top surface of which slopes inwardly and downwardly, a plurality of holes for fastening means passing 15 through said tap, one of said holes being located at approximately the middle of the chamber and receiving an attaching screw adapted to act as a retaining pin for a jingle washer, and an optionally usable jingle washer so dimensioned as 20 to be movable when placed in the sound chamber.

13. A toe tap comprising a tap body hollowed on its upper surface to form a chamber, a locating pin in said chamber for retaining a jingle washer in place, and a jingle washer optionally 25 usable in said tap and dimensioned to be movable therein.

14. A toe tap comprising a tap body hollowed on its upper surface to form a chamber open at the rear of the tap and bounded on the remaining sides by a relatively broad supporting flange, the top surface of said flange sloping downwardly and inwardly in order to insure close contact between the periphery of the flange and the shoe bottom, a jingle washer optionally usable in said 35 tap and dimensioned to be movable therein, and a locating pin cast integrally with said tap and projecting upwardly in said chamber for retaining the jingle washer in place.

15. A jingle tap comprising a metallic tap body 40 adapted to be secured outside of and beneath the bottom of a shoe, said tap body being thin relative to its area and being of generally conventional form in having a periphery shaped to follow the contour of that part of the shoe bottom 45 (toe or heel) to which it is to be attached, said tap body being hollowed on its upper surface to form a chamber open at the top and bounded by a supporting flange, said flange being cut away at one end to form a sound discharge opening, a simple one-piece disc-shaped metallic jingle loosely carried within said chamber, said jingle being smaller in dimension than the chamber and freely movable therein, the ends of the flange at the open end of the tap being turned 50 in until spaced apart by an amount less than the diameter of the jingle.

SALVATORE CAPEZIO.
